UNITED STATES PATENT OFFICE.

CHARLES W. SPONSEL, OF HARTFORD, CONNECTICUT, ASSIGNOR TO THE SPONSEL COMPANY, OF HARTFORD, CONNECTICUT, A CORPORATION OF CONNECTICUT.

MACHINE FOR CALIBRATING GUN-BARRELS.

1,239,534.

Specification of Letters Patent. Patented Sept. 11, 1917.

Original application filed February 28, 1916, Serial No. 80,959. Divided and this application filed July 17, 1916. Serial No. 109,600.

To all whom it may concern:

Be it known that I, CHARLES W. SPONSEL, a citizen of the United States, residing at Hartford, in the county of Hartford and 5 State of Connecticut, have invented a new and useful Improvement in Machines for Calibrating Gun-Barrels, of which the following is a specification.

This invention relates to a machine which 10 is more particularly designed to calibrate or detect and measure the defects in the bores of gun barrels and similar tubes and it is a division of the invention, or is a continuation of so much as is common to the invention 15 shown, described and claimed in my co-pending application Serial No. 80,959, filed February 28, 1916 for machine for straightening gun barrels.

The object of the invention is to provide a 20 simple machine into which gun barrels and similar tubes can be quickly placed, tested and removed, that has means which will electrically indicate small deflections in the bores and mechanically measure the amount 25 of variation from true.

As the invention claimed herein is particularly adapted for use with means by which the barrels or tubes can be bent and straightened until such inaccuracy as is indicated by the electrical means and measured 30 by the mechanical means is overcome, it is illustrated and described as incorporated in a gun barrel straightening machine.

The machine illustrated has yielding centers for supporting a barrel at the breech and muzzle. These centers are mounted so that they may be moved sidewise of the machine for carrying the barrel lengthwise, and they are also capable of upward movement 35 so as to allow the ends to spring upwardly when the barrel is being straightened. A wire, secured at one end by a fixed clamp, is arranged to be threaded through the barrel and supporting centers, and after its other 40 end is secured by a yielding clamp, be drawn tight and held taut with a spring tension. The wire clamp supports are mounted so that they may be lowered and raised a slight 45 distance and carry the wire down or up, this distance being measurable by a micrometer gage. The wire is connected in an electric circuit containing lamps, and at the 50 middle of the machine is provided with a conducting feeler or contact that is adapted

to be engaged with or disengaged from the 55 wall of the bore of the barrel as the wire is lowered or raised. One of the circuit terminals is connected with the wire, the supports of which are properly insulated, and the other terminal is grounded on the machine. The circuit is so planned that when 60 the wire contact is caused to touch any point along the bore of the barrel the circuit conditions will be changed in such manner that the lamps will show the altered relation, and 65 the gage will show the amount of movement which caused the change. Associated and co-operating with the electrical indicating and mechanical measuring means is 70 mechanism arranged to bend the barrel while in testing position and restore the electrical condition, and thus show a rectification of whatever irregularity is indicated and measured, although the bending mechanism forms no part of the invention claimed 75 herein.

Figure 1 of the accompanying drawings shows a front elevation of the machine. Fig. 2 shows a plan. Fig. 3 is a diagrammatic illustration of the method of indicating the accuracy of the bore. Fig. 4 is a view of the electrical contact that is threaded through the barrel. Fig. 5 is a face view of the same. Fig. 6 shows an elevation of the machine. Fig. 7 is a vertical section on the 80 plane indicated by the line 7—7 on Fig. 2. Fig. 8 is a vertical longitudinal section through the barrel. Fig. 9 is a sectional view showing the wire clamping and stretching mechanism at the left hand end of the machine. Fig. 10 shows a side view of one of the barrel supporting centers and the adjacent mechanism. Fig. 11 shows a plan of the same. Fig. 12 is a vertical section on the 85 plane indicated by the dotted line 12—12 on Fig. 11.

The bed 1 of the machine is mounted on a column 2 having a widened base 3. A slide 4 is arranged to move back and forth in a guideway that extends from side to side in 90 the top of the bed. On the bottom of this slide is a rack 5 engaging with which is a pinion 6 on a shaft 7 that at the front is provided with a hand wheel 8. A head 9 is adjustably fastened on the top of the slide 95 near each end. Pivoted to each head is an arm 10, and hinged to each arm is a block 11 which holds a tubular barrel supporting

center 12. The centers at the top are slotted from end to end and the ends of the centers which project toward each other are tapered. Each arm is pressed downward by 5 a flat spring 13 and each block is pressed forward by a spiral spring 14 and plunger 15. Each block is guided at the front when it moves up and down by a vertical groove in the back surface of the front part of the head. Each center is pushed toward the 10 middle of the machine by a flat spring 16, that engages with a pin 18 which extends downward from the center (Fig. 10) and the center at the left is arranged to be 15 drawn back by a hand lever 17 that is pivoted to the block by screw 171 and engages with a pin 18 which projects from the center. To put a barrel into the machine the center at the left is drawn back and 20 when one end of the barrel is placed on the center at the right the left center is allowed to spring forward into the barrel at that end. When mounted this way the barrel can be moved lengthwise across the machine 25 by turning the hand wheel at the front. The heads are located on the slide according to the length of the barrels to be straightened.

The indicator wire 19, which is designed 30 to pass through the barrel and through the barrel supporting centers, is secured at its ends by clamp levers 20 which are pivotally mounted on blocks 21 secured at the ends of rocker arms 22 that project forwardly 35 from a rocker shaft 23 that extends lengthwise of the machine at the back. The rocker shaft is preferably mounted in fiber bushings 24 placed in brackets 25 attached to the back of the bed so it can rotate without 40 moving longitudinally, and will be electrically insulated from the rest of the machine. The clamp levers are provided with hand screws 26 which, when turned one way, cause the jaw ends of the clamps to bite the 45 ends of the wire against teeth on the clamp blocks, and when turned the other way allow the jaws to open and release the ends of the wire. The clamp block with the clamp lever at the left hand end of the machine is 50 slidable horizontally in the end of the arm for tightening the wire. This clamp block has a threaded stem 27 on which turns a hand nut 28. A spring 29 is arranged on the threaded stem between the nut and the 55 end of the arm so that when the nut is turned up for tightening the wire the spring will be compressed and thus hold the wire taut but with a yielding tension. Bars 30 extend across the top from the front of the 60 arms 22, which carry the wire clamps, to other arms 31 which are fastened to the rocker shaft near the middle of the machine. These bars not only stiffen the wire clamp supports and insure that they move together, but they are arranged so that they

will be engaged and lifted by the arms 10 which carry the barrel centers when in bending the barrel down at the middle the ends spring up. Thus if the end of a barrel 70 springs up when it is being bent and the center which supports that end of the barrel is lifted, the lever which carries the center holding block engages the bar above it and carries it up. This lifts the wire clamps so that the wire will not be sheared off or 75 broken by the bending of the barrel.

The rocker shaft has attached to it a lever arm 32 that engages a nut 33 held from rotation by a bracket 34 fastened to the back of the bed. Turning in this nut is the rear end of the arbor 35 on the front end of which is secured the hand wheel 36. Frictionally held on the hub of the hand wheel by a thumb screw 37 with a tapered inner end and a plunger 38 with a tapered inner end is the 80 index wheel 58. When the tapered inner end of the screw is forced against the tapered inner end of the plunger the latter is forced out against the inner wall of the hub of the index wheel. The index wheel is 85 graduated on its periphery in thousands of an inch. When the index wheel is turned one way the nut is drawn forward in such manner as to cause the lever to rock the shaft and turn up the arms and raise the 90 indicator wire. When the index wheel is turned in the opposite direction the nut is moved backward and the weight of the arms and connected parts carries the indicator wire, downward. If the thumb screw is 95 loosened the graduated index wheel is released so that it can be turned around and set to zero. As the rocker lever is not attached to the nut, but merely held against it by gravity, the parts are free so that the 100 wire may be lifted whenever the centers are carried up by any bending of a barrel. The lower end of the rocker lever is insulated from the nut by a piece of insulation 39.

Wedge shaped blocks 40 are mounted so 105 that they are free to be moved toward the front and back in slides 41 that are free to be moved along the top of the bed from side to side. By moving the slides 110 longitudinally of the machine the wedge shaped blocks may be located anywhere that it is desired along the length of the barrel, and by pushing the blocks backward they may be brought into contact at the required places with the barrel held by 115 the centers. At the center of the machine and projecting forwardly is a bending arm 120 42 that is pivoted on pin 422 (Fig. 7) to the bed near the back and at its front end over the center of the barrel is provided with a heavy screw 43 which may be turned down or up by hand or by means of a wrench. The rear end of the bending arm is pivotally connected with the upper end of a link 125 44 that is supported by a link 45 which is 130

jointed to the column. The lower end of the link 44 is connected by a short toggle arm 460 with the bent end of the treadle lever which is pivoted to the base and at the 5 front of the machine is provided with a foot pad 47. When the treadle is depressed, by means of this toggle and link connection the bending arm is forced down with great power. The treadle may be held down by a 10 lock bar 48 if desired, or it may be locked up by a safety catch 49. The treadle is raised by a spring 50 arranged inside of the column. A yielding cushion 51 is attached to the back of the column in such manner 15 as to prevent the toggle from becoming locked on center.

Small lamps 52, preferably red and green, are located in a box 53 attached to the front of the bed and adjacent to this is a switch 20 54. Secured to the back of the bed may be a fuse block 55 and attached to the under-side may be a transformer 56. Line wires are connected with the fuse block which is connected with the switch. The circuit 25 wires run from the switch to the transformer and then to the lamps. One end of the circuit is grounded on the machine, while the other end is connected with the indicator wire, the supports of which are, as 30 above described, electrically insulated from the rest of the machine. On the indicator wire at the center of the machine and directly below the bending screw is a conducting feeler or contact 57. The conducting 35 feeler on the wire at the middle of the machine and below the bending screw is arranged so as to always point downward.

In using this machine the ends of the barrel which have been slightly reamed out are 40 placed on the centers with the indicator wire threaded through the barrel and laid in the centers. The free end of the wire is then clamped and the wire drawn taut. The barrel may first, if necessary, be rough straightened by rotating it on the centers and moving it along until the highest spot of the bend comes beneath the bending screw. The blocks are moved along to the desired 45 place and pushed back, and then the bending screw is brought down by pressing on the treadle. This may be continued until the barrel is in such condition that the indicator wire will not touch at either end. When this has been accomplished the barrel 50 is moved along until one end is at the center and then the wire is lowered by turning the index wheel until the contact touches the bottom of the bore of the barrel. This grounds the circuit and one of the lights 55 will go out. The index wheel is then set to zero. The barrel is then rotated to see if the center on which it is mounted is true with the bore. The barrel may then be pushed over until the other end is at the 60 center. The wire is again lowered until the

contact engages the bottom of the bore and the light goes out. If the ends are true the index will show zero. The barrel is then turned around to see whether it is mounted true on the center at this end. After this 70 the barrel is pushed along from end to end and rotated to find out where the high spots are, how long the curves are, and the amount of deflection. The barrel is then moved along until the highest point is beneath the 75 bending screw and the blocks pushed beneath it. The treadle is depressed, bringing down the bending screw and bending the barrel. This is repeated until with the index at zero the lights will both stay on as 80 the barrel is rotated. When the barrel can be moved to every position and can be rotated in any position and both lights will stay lighted with the index at zero, it is known that the bore is absolutely straight. 85 As a very small current is employed and the lamps are small and the contact is very delicate, deflections of .0001 of an inch in the barrel will be indicated.

The invention claimed is:

1. A machine for calibrating gun barrels having means for supporting a barrel, a wire adapted to be threaded through the barrel, means for holding the wire taut when so threaded, means for imparting a relative 95 transverse movement between the wire holding means and the barrel, a contact on the wire and adapted to be engaged with any point along the wall of the bore of the barrel, and means for indicating outside the 100 barrel the engagement of the contact therein, said means being automatically controlled by such engagement.

2. A machine for calibrating gun barrels having supports for a barrel, means for 105 moving the barrel supports together in the direction of the axis of the barrel, a wire adapted to be threaded through the barrel, means for holding the wire taut when so threaded, means for imparting a relative 110 transverse movement between the wire holding means and the barrel, a contact on the wire and adapted to be engaged with any point along the wall of the bore of the barrel, and means for indicating outside the 115 barrel the engagement of the contact therein, said means being automatically controlled by such engagement.

3. A machine for calibrating gun barrels having means for supporting a barrel, a 120 wire adapted to be threaded through the barrel, means for holding the wire taut when so threaded, means for moving the wire holding means transversely of the barrel, a contact on the wire and adapted to be engaged with any point along the wall of the bore of the barrel, and means for indicating outside the barrel the engagement of the contact therein, said means being automatically 125 controlled by such engagement.

4. A machine for calibrating gun barrels having supports for a barrel, means for moving the barrel supports together in the direction of the axis of the barrel, a wire 5 adapted to be threaded through the barrel, means for holding the wire taut when so threaded, means for moving the wire holding means transversely of the barrel, a contact on the wire and adapted to be engaged with any point along the wall of the bore of the barrel, and means for indicating outside the barrel the engagement of the contact therein, said means being automatically controlled by such engagement.
- 15 5. A machine for calibrating gun barrels having supports for a barrel, means for moving the barrel supports together in the direction of the axis of the barrel, a wire adapted to be threaded through the barrel, 20 means for holding the wire taut when so threaded, means for imparting relative side-wise movement between the wire holding means and the barrel, a contact on the wire and adapted to be engaged with any point 25 along the wall of the bore of the barrel, an electrical circuit adapted to be closed by such engagement of said contact, and means controlled by closure of said circuit for indicating the engagement of the contact with the wall of the bore.
- 30 6. A machine for calibrating gun barrels having means for supporting a barrel, a wire adapted to be threaded through the barrel, means for holding the wire taut when so 35 threaded, means for moving the wire holding means transversely of the barrel, a contact on the wire and adapted to be engaged with any point along the wall of the bore of the barrel, an electric circuit adapted to be 40 closed by such engagement of said contact, and means controlled by closure of said circuit for indicating the engagement of the contact with the wall of the bore.
7. A machine for calibrating gun barrels 45 having supports for a barrel, means for moving the barrel supports together in the

direction of the axis of the barrel, a wire adapted to be threaded through the barrel, means for holding the wire taut when so threaded, means for moving the wire holding means transversely of the barrel, a contact on the wire and adapted to be engaged with any point along the bore of the barrel, an electrical circuit including the wire, contact and barrel supports and means for indicating the engagement of the contact with the wall of the bore of a barrel held by said support.

8. A machine for calibrating gun barrels having supports for a barrel, means for moving the barrel supports together in the direction of the axis of the barrel, an electric circuit including the barrel supports and a contact adapted to be located in the bore of the barrel, and electrically excited means included in said circuit to indicate engagement of said contact with the wall of the bore.

9. A machine for calibrating gun barrels having means for supporting a barrel and carrying it longitudinally of its axis, an electric circuit including the barrel supporting means and a conducting contact adapted to be inserted into the bore of the barrel, means for moving the electrical contact transversely of the axis of the barrel, and electrically excited means included in said circuit to indicate the engagement of said contact with the wall of the bore of the barrel.

10. A machine for calibrating gun barrels having means for supporting a barrel, an electrical conductor adapted to be passed into the bore of a barrel held by said supporting means, a conducting contact on said conductor and adapted to be engaged with any part of the wall of the bore of such barrel, a source of electrical energy connected with said conductor and with a barrel placed in the supporting means, and an electric lamp interposed in the electrical circuit.

CHARLES W. SPONSEL.
